(57) **CLAIM**

The ornamental design for a circular fan grill, as shown and described.

DESCRIPTION

FIG. 1 is a right side front perspective view of a circular fan grill showing my new design;

FIG. 2 is a front elevation view thereof;

FIG. 3 is a rear elevation view thereof; and,

FIG. 4 is a side elevation view thereof, the opposite side being a mirror image of that shown.

The broken line showing of environmental structure in FIGS. 1-4 is for illustrative purposes only and forms no part of the claimed design.

1 Claim, 4 Drawing Sheets
